SANDAL

Tatsumi Hayakawa, Fukuyama City, Japan

Application February 8, 1957, Serial No. 44,810

Claims priority, application Japan November 5, 1956

Term of patent 14 years

(Cl. D7—7)

Fig. 1.

Fig. 2.

Fig. 3.

Fig. 4.

Fig. 1 is a top elevation of the sandal;

Fig. 2 is a side plan view of the sandal;

Fig. 3 is a bottom plan view of the sandal; and

Fig. 4 is a section along line 4—4 of Fig. 1.

The characteristic feature of my sandal design resides in the combination on the sandal disclosed of the specific textured upper surface in association with the specific patterned bottom surface and the configuration of the straps, all as shown.

I claim:

The ornamental design for a sandal, as shown and described.
